UNITED STATES PATENT OFFICE.

WILLIAM RAAB, OF CEDAR FALLS, IOWA.

CHIMNEY.

SPECIFICATION forming part of Letters Patent No. 242,044, dated May 24, 1881.

Application filed November 13, 1880. (No model.)

To all whom it may concern:

Be it known that I, WILLIAM RAAB, of Cedar Falls, in the county of Black Hawk and State of Iowa, have invented a new and valuable Improvement in Chimneys; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a perspective of my device. Fig. 2 is a vertical sectional view, and Fig. 3 is a transverse sectional view of the same.

This invention relates to the construction of chimneys.

The invention consists in the devices hereinafter described.

In the annexed drawings, A represents a chimney made of any desired shape and in one or more than one piece secured tightly together. This chimney is constructed with three flues, B C D. The central flue, B, is the ordinary smoke-flue, and reaches from an opening in the top of the chimney down to the furnace-hole below. Next to this is the hot-air flue C, which commences at the bottom of the chimney and passes up the same alongside the smoke-flue, being closed at the top and opening through registers E into the apartments. Outside of this flue C is a ventilating-flue, D, having openings d at the top leading outside the building, and openings e at the bottom leading inside the building.

The chimney is properly braced throughout its length by ribs a passing lengthwise the two outer flues.

F represents a seat for a range or small stove,

which is connected with a tube, H, which passes up through one side of hot-air flue C and down the same, and by an elbow, b, enters smoke-flue B at the bottom.

I is a chamber below for readily reaching the end c b' of tube H.

Fire being made in the furnace, the smoke passes up flue B, and the air in flue C is heated, and passing through registers E heats the apartments. The air in flue D, being warmed by the passage of hot air through flue C, rising induces a current from openings e to d, thereby ventilating the building. When the wind blows against the side of the chimney it forces air down the flue D and drives fresh air into the building. By the use of this outside ventilating-flue the chimney is kept from getting overheated.

When there is no fire in the furnace below one may be made in the range above, and the products of combustion passing through tube H and out of flue B will produce the same result.

What I claim is—

1. A chimney having a central smoke-flue, an outside ventilating-flue, and an intermediate hot-air flue, as set forth.

2. The tube H, passing through the hot-air flue C, up and returned, having one end leading into the smoke-flue and the other adapted to be fitted to a stove or range, as set forth.

In testimony that I claim the above I have hereunto subscribed my name in the presence of two witnesses.

WILLIAM RAAB.
